(57) **CLAIM**

The ornamental design for a bottle opener for electronic cigarette, as shown and described.

DESCRIPTION

FIG. 1 is an isometric view of the bottle opener for electronic cigarette, which embodies my design;

FIG. 2 is a side view of the thereof;

FIG. 3 is a side view of the thereof;

FIG. 4 is a top plan view of the thereof;

FIG. 5 is a bottom plan view of the thereof;

FIG. 6 is a side view of the thereof;

FIG. 7 is a side view of the thereof; and,

FIG. 8 is an isometric view of the bottle opener for electronic cigarette in a position of use.

The electronic cigarette shown in dotted lines in FIG. 8 is shown for environmental purposes only and forms no part of the claimed design.
